UNITED STATES PATENT OFFICE.

THEODORE H. SCHMUTZ, OF CHANUTE, KANSAS, ASSIGNOR OF ONE-HALF TO
W. R. CLINE, OF ERIE, KANSAS.

DESIGN FOR A BALANCE-PUMP MEMBER.

SPECIFICATION forming part of Design No. 35,533, dated December 31, 1901.

Application filed November 21, 1901. Serial No. 83,193. Term of patent 14 years.

To all whom it may concern:

Be it known that I, THEODORE H. SCHMUTZ, a citizen of the United States, residing at Chanute, in the county of Neosho and State of Kansas, have invented and produced a new and original Design for Balance-Pump Members, of which the following is a specification.

My invention relates to balance-pump members; and my object is to produce a new and original design for the same which is both useful and ornamental.

In the accompanying drawing, which shows a perspective view of the design, the leading or material feature consists in a vertical stand-pipe provided with a lateral projecting spout at its upper end and at its lower end with branch pipes, which extend for the greater part of their length vertically and parallel with each other and the stand-pipe and have their upper ends converging upwardly and forming a junction with the stand-pipe, also in the cylinder between and parallel with the vertical portions of the stand-pipe, said cylinder being of shorter length than said vertical portions of the branch pipes.

Minor features of the design reside in the

enlargements or collars at the lower end of the stand-pipe and in the similar but smaller enlargements or collars at the junction of the straight portions of the branch pipes and their 30 upwardly-converging ends.

In the said drawing, 1 designates the stand-pipe; 2, the spout at the upper end of the same; 3, the collars at its lower end; 4, the straight portions of the branch pipes; 5, the 35 converging portions of the same; 6, the collars or enlargements at the junction of said straight and converging portions, and 7 the cylinder between and extending parallel with the said branch pipes.

Having thus described the invention, what I claim as new, and desire to secure by Letters Patent, is—

The design for a balance-pump member, substantially as herein shown and described. 45

In testimony whereof I affix my signature in the presence of two witnesses.

THEODORE H. SCHMUTZ.
